CHARLES A. CULVER, OF NORTHFIELD, MINNESOTA, ASSIGNOR, BY MESNE ASSIGNMENTS, TO FEDERAL TELEGRAPH COMPANY, A CORPORATION OF CALIFORNIA

MODULATING SYSTEM

Application filed July 16, 1926. Serial No. 122,985.

This invention relates to control or modulation circuits for the output of a high frequency electrical oscillator, and more particularly to a system of modulation for use in connection with radio broadcasting.

An object of this invention is to effect an improvement in the means whereby voice generated potentials may be made to control the high frequency output of a radio transmitter, and more particularly to provide a more flexible system whereby the potential on the oscillator and modulator tubes may be independently controlled.

Another object is to reduce the amplitude of the non-signalling carrier wave.

Still another object of the invention is to reduce the non-signalling plate current in the transformer supplying plate potential to the power tubes to a minimum, thus avoiding distortion due to high flux density.

My invention will be more fully understood from the specification hereinafter following by reference to the accompanying diagram which shows the arrangement of a radio transmitter employing the principles of my invention.

The component parts of the circuit consist of the inductance L_1 and L_2 , capacitances C_1 and C_2 , and the power tube VT_1 together with the usual filament supply and constitute a typical high frequency generator circuit, the exact type of oscillating circuit being immaterial. The energy supply for the oscillator consists of a balanced organization, the output of which is applied to the plate circuit of the oscillator above indicated through the transformer T_1 . This modulator organization consists of tubes VT_2 and VT_3 together with the usual accessory parts as shown. The condenser C_3 is of low impedance to currents of audio frequency and serves to insulate the grid of the power tube VT_1 from the constant plate potential but does, however, permit the passage of any currents of audio frequency which may obtain in the secondary of the transformer T_1 . A common source of positive constant potential B supplies both the plates of the modulator tubes and the power tube. However, it will be understood that the power tube and

the modulator tubes may have independent potential supplies if so desired.

Voice generated potentials are impressed on the grid of the modulator tubes VT_2 and VT_3 by means of the microphone M acting in the usual manner in the primary of the transformer T_2 , or through suitable audio frequency amplifiers. The variations in the grid potential of the tubes VT_2 and VT_3 thus effected cause a variation in the plate current I_m through said tubes and hence through the primary P of the transformer T_1 . The ratio of the turns in the primary P and secondary S of the transformer T_1 are so chosen that, because of the variations in the primary current I_m , there will be developed an alternating potential of audio frequency in the secondary of said transformer of suitable value to properly operate the power tube VT_1 . Under certain circumstances it may be found advisable to apply to the plate of the power tube VT_1 a constant potential of sufficient magnitude to cause feeble oscillations to obtain. The exact value of this constant potential is in any given case controlled by the series resistance R_2 .

As shown in the drawings the high frequency power tube has impressed upon it a relatively low direct current potential from source B , this direct current potential being of a value just great enough to maintain the tube in an oscillating condition. The working potential is supplied by the transformer T_1 . The input side of T_1 constitutes the output circuit of a balanced amplifier, but the balanced feature is not essential. It, however, possesses certain advantages, particularly in that it makes possible the working of the iron at a relatively low non-signaling flux density value. The chief point is that the working anode potential is not supplied from a battery or direct current generator but from a source of potential which gives an alternating wave form corresponding to the modulating sound wave, and that said potential is produced by means of a tube or tubes acting as variable resistances in the primary of said transformers.

As a result of the operation of the various

components of the organization above specified the principal plate supply of the power tube will be an alternating current of the same frequency and wave form as the voice 5 generated currents in the secondary of the microphone circuit. Thus the output of the high frequency power circuit will have a wave form corresponding to the said voice currents, modulation thus being effected.

10 An advantage of the system of modulating constituting this invention is that the direct current and audio frequency alternating current components of the plate current of the power tube may be adjusted independently of one another.

15 Another advantage of my invention is that, because of the balanced condition in the primary of the transformer T_1 , and the very low or zero direct current value in the secondary, 20 the iron of the transformer T_1 will be worked at a relatively low permanent flux density and hence distortion of the wave form due to high flux density will be absent. In previous attempts to design an arrangement whereby 25 the plate of the power tube might be supplied with an audio frequency potential, there has existed a direct current component in the primary of the transformer supplying that potential.

30 Still another advantage of this system of modulation is that, because of the very low constant plate current component in the power tube the amplitude of the carrier wave is maintained at an extremely low value, and 35 in fact may, if desired, be reduced to zero. As a result of this condition the general interference caused by the non-signalling radiation is substantially reduced, and in addition the over-all efficiency of the transmitting organization is increased.

40 Having described my invention in one of its preferred embodiments, I desire that it be understood that modifications may be made and that no limitations upon the invention 45 are intended other than are imposed by the scope of the appended claims.

What I claim as new and desire to secure by Letters Patent of the United States is as follows:

50 1. A modulation system comprising a plurality of electron tubes each having grid, filament and plate electrodes, input and output circuits interconnecting said electrodes with the circuits of one of said electron tubes 55 mutually coupled and connected with a source of potential for the generation of high frequency oscillations, a transformer having primary and secondary windings with the secondary winding thereof connected in circuit with said first mentioned electron tube, one of the terminals of said secondary winding being connected directly to the plate electrode of said first mentioned electron tube, a microphone circuit, a pair of said electron tubes 60 being connected in balanced relationship and

disposed between said microphone circuit and the primary winding of said transformer, whereby variable audio frequency currents may be impressed upon said first mentioned electron tube and superimposed upon the potential supplied by said source for controlling the amplitude of the high frequency currents generated in the circuits thereof, and means for controlling said source of potential independently of said variable audio frequency currents.

2. A modulation system comprising a plurality of electron tubes each having grid, filament and plate electrodes, input and output circuits interconnecting said electrodes with the circuits of one of said electron tubes mutually coupled for the generation of high frequency oscillations, a transformer having primary and secondary windings, with the secondary winding thereof connected in circuit with said first mentioned electron tube, a microphone circuit, and a pair of said electron tubes connected in balanced relationship between said microphone circuit and primary winding of said transformer, a mid-tap on the primary winding of said transformer, a source of potential for supplying space current to all of said electron tubes, and a resistance in circuit with said source of potential for controlling the magnitude of the potential of said source applied to said electron tube, high frequency oscillation generator, said source of potential being adjustably controlled independent of current in said primary winding, said source connected with said mid-tap in said primary winding and with the output circuit of said first mentioned electron tube and operating to sustain oscillations at a predetermined amplitude whereby variable alternating current may be impressed upon said first mentioned electron tube and superimposed upon the oscillations sustained therein for controlling the amplitude of said oscillations in accordance with the operation of said microphone circuit.

3. A system of modulation comprising a plurality of electron tubes each having grid, filament and plate electrodes, input and output circuits interconnecting said electrodes, with the circuits of one of said tubes mutually coupled for the generation of high frequency oscillations, a transformer having primary and secondary windings, with the secondary winding thereof connected in circuit with the first mentioned electron tube, a microphone circuit, a pair of electron tubes connected in balanced relationship between said microphone circuit and the primary winding of said transformer, a source of high potential for supplying space current to all of said electron tubes, and connections between said source and a midpoint of said primary winding and with the plate circuit of said first mentioned electron tube, and means interposed in said last mentioned connection for
